UNITED STATES PATENT OFFICE.

TAYLOR E. DANIELS, OF CHICAGO, ILLINOIS.

EXCAVATING CUTTING-MACHINE.

SPECIFICATION forming part of Letters Patent No. 726,877, dated May 5, 1903.

Application filed April 14, 1902. Serial No. 102,819. (No model.)

To all whom it may concern:

Be it known that I, TAYLOR E. DANIELS, a citizen of the United States, residing at Chicago, in the county of Cook and State of Illinois, have invented a new and useful Improvement in Excavating Cutting-Machines, of which the following is a specification.

My invention relates to an improvement in the class of machines used for mining and other excavating purposes requiring the cutting operation to be extended through hard material, such as rock, as well as through softer material that may be encountered, in which the cutters are provided at intervals on an endless chain adapted to be introduced farther and farther into the excavation as the work proceeds and to be withdrawn therefrom.

My object, which includes providing a generally improved construction of machine in the class referred to, is primarily to adapt the endless-chain cutting device to be incased as the work progresses in the opening formed by the operation, thereby to provide a casing in the opening to prevent it from caving in.

To accomplish my aforesaid primary object, since the cross-sectional dimensions of the excavation may not be greater than those of the endless-chain cutting apparatus and since provision must be made for admitting both the external casing and the cutting apparatus it surrounds simultaneously into the excavation, I provide at least two endless chains carrying the cutting-tools and preferably, also, elevator-buckets to work side by side and also, by preference, a rotary cutter-head between the chains at their lower end to cut the material that might otherwise be missed by them, being between the planes of their action, and which would obstruct the downward feed of the cutting apparatus, and consequently the progress of its work. The provision thus suggested of a plurality of the endless-chain cutting devices enables me to expand them toward the lower working end of the machine and to contract them above the lower end into the casing to an extent sufficient to compensate for the thickness of the sides of the casing, which extend across the faces of the cutting-chains, and I also provide for cutting the excavation large enough at the sides of the casing which extend across

the edges of the cutting-chains to admit the thickness of those sides of the casing, all as hereinafter described.

An incident of the employment of a plurality of the endless-chain cutting devices is that it enables them to be actuated in relatively contrary directions, with the very important advantage, due to the checking effect of one upon the other, of preventing a tendency of the cutting device to creep, and thus cut out of alinement.

Referring to the accompanying drawings, Figure 1 is a view in front elevation of my improved machine with a portion of the casing removed; Fig. 2, a view of the same in side elevation, showing the endless-chain cutting apparatus adjusted to an angle; Fig. 3, a broken view showing in elevation the worm-gear mechanism for feeding and raising the cutting apparatus on its supporting standard; Fig. 4, a broken vertical sectional view of the machine, enlarged over the scale observed in the preceding figures; Fig. 5, a section taken at the line A A on Fig. 4; Fig. 6, a broken view of the lower portion of the cutting apparatus with the endless cutter-carrying chains removed to disclose the guide-grooves for controlling them; Fig. 7, a view in side elevation of the interposed cutting-head; Fig. 8, a partly-broken enlarged view, in front elevation, of several of the connected cutter and bucket carrying links of which each of the endless chains is formed; Fig. 9, a view of the same in side elevation with a bucket shown in cross-section; and Fig. 10, a section taken at the line B B on Fig. 9 and viewed in the direction of the arrows.

On a support in the preferred form shown of a vertical standard *a*, rising from a base *b*, is a longitudinal ratchet *c*. The standard is surrounded by a vertically-movable rotatable sleeve *d*, carrying horizontally upon its upper end to rotate it a cog-wheel *e*, the standard also carrying about the sleeve *d*, to move up and down with it, a bracket *f*, through the medium of which the operating parts of the machine are supported on the standard. At one side of the machine (regarding that presented to view in Fig. 1 as the front) the bracket ends in a plate-shaped head *g*, having at opposite sides of its vertical center two substantially arc-shaped concentric slots *h*.

and *i* for an adjusting purpose hereinafter described, each about ninety degrees in length. Concentric with the head *g* a horizontal tubular bearing *j* is provided on the bracket for 5 a rotary sleeve or hollow shaft *K*, carrying on its inner projecting end a beveled gear-wheel *l* and on its outer projecting end a sprocket-wheel *m*. A rotary shaft *n* extends through 10 and is journaled in the sleeve *k* and carries on its inner projecting end a beveled gear-wheel *o* and on its outer projecting end a sprocket-wheel *p*. On the opposite side of the bracket is shown in alignment with the bearing *k* a horizontal tubular bearing *q* for a rotary 15 shaft *r*, carrying on its inner projecting end a beveled gear-wheel *s* like the gear-wheel *o* and on its outer projecting end a grindstone *t* for sharpening the cutting-tools hereinafter described. Respectively above and below 20 the gear-wheels *o* *s* are secured on the standard-sleeve *d* a beveled gear-wheel *u*, meshing with the gears *o* and *s*, and a beveled gear-wheel *v*, meshing with the gear *l*. On the top of the plate *g* is provided a bearing 25 *w* for the lower end of a vertical rotary shaft *x*, carrying to rotate with it a pinion *y*, in mesh with the cog-wheel *e*, and a crown-faced drive-belt pulley *z*, from which the machine is geared with suitable driving power.

30 An endless chain 1, preferably constructed as hereinafter described, is hung from the sprocket-wheel *m* and passes about a lower sprocket-wheel 3 of greater diameter journaled on a shaft 5, fastened in the casing hereinafter described and having journaled upon it another sprocket-wheel 4 of the same size as the wheel 3, about which passes from the sprocket-wheel *p* another endless chain 2 like the endless chain 1. Between the sprocket-40 wheels 3 and 4 on the shaft 5 and rigidly fastened to one of them to rotate with it is a disk-shaped cutter-head 6, having at intervals on its periphery cutting-teeth 7, which project beyond the sprocket-teeth on the wheels 3 and 4.

45 An upper tautening-bar 8 fits between the opposite sides of the two chains 1 and 2 and may be rigidly and adjustably fastened to extend at any angle desired within about ninety degrees of a circle to the outer face of the 50 plate *g*, as represented in Fig. 2, by bolts passing through the slots *h* *i* and secured by nuts. The sprocket-teeth on the wheels *m* and *p* in their rotation clear the upper end of the bar 8 by passing through recesses 9 9 therein. A 55 lower tautening-bar 10, having an offset toward its upper end presenting a shoulder 12, overlaps the lower end of the bar 8, to which it is adjustably fastened by a bolt 13, secured by a nut and passing through the bar 8 and 60 through an elongated slot 14 in the overlapping portion of the bar 10, in the lower end of which are also recesses 9 9 for clearance of the sprockets on the wheels 3 and 4. Between the lower end of the bar 8 and the shoulder 12 65 on the upper end portion of the bar 10 are inserted right and left adjusting-screws 15 15 for tightening the bar 10 against the lower

sprocket-wheels for the purpose of tautening the chains and for loosening the lower bar for slackening the chains.

70 On each of the opposite sides of the bars 8 and 10 on which the chains travel are formed, as shown of the side presented to view in Fig. 6, T-shaped guide-grooves 16 16, straight and parallel nearly to their lower ends, whence 75 they diverge outwardly to coincide at their lower extremities with the recesses 9 9 in the lower extremity of the bar 10.

Each of the endless chains is formed of a series of connected links 17, some of which 80 carry cutting-tools 18, preferably of the form shown, while others carry scoop-shaped elevator-buckets 19. The links equipped with cutting-tools and those equipped with the scoops may be relatively arranged in each 85 chain, according to particular requirement, thus to alternate with each other or otherwise. The number of cutting-tools on the several links equipped with them may vary, some carrying one tool each, others two, and 90 still others three each, and the latter number may be exceeded on some links, if desired, and the relative positions of the cutting-tools on the successive cutter-links may also be arranged according to requirement. 95 From the backs of the links and preferably from the backs only of those carrying cutting-tools and buckets there project T-shaped stems 21, which extend at their heads into and are confined in the grooves 16 16 to 100 guide the endless chains therein.

A rectangular sheet-metal casing 20 is shown enveloping the chains, extending on the two sides, one of which is presented in Fig. 2 from the plane near the tops of the 105 sprocket-wheels 3 4 and on the two other sides from near the lower portions of these wheels upward to the bolt 13, which serves to fasten the casing in place through two opposite of the four sheet-metal plates of which 110 it is formed, the remaining two plates, (one of which is presented in Fig. 2,) which extend at right angles to those shown in Fig. 4, being fastened to the latter. As hereinbefore stated, the shaft 5 for the lower sprocket-wheels is rigidly fastened in the opposite 115 longer sides of this casing.

On the lower end of the standard-sleeve *d* is a transverse journal-bearing 22, divided by an opening 23 in the sleeve, through which a 120 pinion 24 on a shaft 25, journaled in said bearing, meshes with the rack *c* on the standard and sustains thereon the sleeve *d* and bracket *f* and parts carried by them. The shaft 25 carries on its end which projects beyond the bearing a worm-wheel 26, with which meshes a worm-shaft 27, journaled in a bearing 28, formed in the bracket *f*, and carrying on its outer end a hand-wheel 29. This worm-gear mechanism serves for feeding the endless-chain cutting devices toward the work as it progresses and for withdrawing it therefrom.

The operation is as follows: The machine

being placed where the work is to be performed and the pulley z geared by a belt 30 with the driving power, (not shown,) the bar 8 is adjusted on the plate g to extend the cutting-chains and head 6 toward the work, thus parallel with the standard a if the work is below it or at a suitable angle to the standard if the work is to one side of it. The pulley z being then set in motion causes the 10 gears connecting it with the sleeve d to rotate the latter and with it the beveled gears u v , the former driving the sprocket m to drive the chain 1 in one direction and the latter driving the sprocket p to drive the chain 2 in 15 the contrary direction. The cutting-tools on the chains attack the work they encounter in passing about the sprocket-wheels 3 4 and produce, with the coöperation of the cutting-disk 6, the initial excavation, and as the work 20 progresses the hand-wheel 29 is turned to lower the sleeve d accordingly and with it the bracket f and gearing upon it and feed the cutting devices to the work. As will be noticed, by causing the chains to travel in relatively 25 contrary directions the cutting-tools in their operation against the work act in opposite directions, thus against each other, as it were, with the consequent tendency to keep the cutting mechanism in line with the work 30 by preventing that mechanism from creeping, and thus straining the machine, besides forming an irregular hole. It will, moreover, be understood that the speed of feeding will vary with the progress of the work, being slower 35 through rock and other material of great resistance than through softer material, as soil.

As the depth increases of the excavation being made it is desirable to insert a casing into it to reinforce it against caving in. Accordingly 40 I provide about the chains the section of the casing 20, the thickness of the ends of which (or shorter sides extending across the peripheries of the sprockets) is sufficient to widen it to about the diameter of 45 the excavation, which is as much greater than the width across the edges of the chains above the lower sprocket-wheels 3 4 as the latter are of greater diameter than the upper sprocket-wheels. The diameter of the excavation cross-wise 50 of the faces of the chains is increased sufficiently to admit into it the thickness of the corresponding sides of the casing by projecting at intervals on each chain some of the cutting-tools 18, as shown of the two 55 outer ones of the series of three in Fig. 8, beyond the lateral edges of the chain. With this construction and the section of casing 20 in place, as shown, as the chains 1 and 2 pass from the casing-section about the lower 60 sprocket-wheels they spread on their descending sides, owing to the greater diameter of the lower than the upper sprocket-wheels, and they contract on their ascending sides toward the narrower upper sprocket-wheels 65 to be omitted into the casing at its lower end and pass through it from the lower sprocket-wheels. Above the plane of the lower

sprocket-wheels the chains travel parallel in the straight sections of the grooves 16; but their descending portions in attaining the diverging lower sections of the grooves below the lower end of the shorter sides of the casing spread outward to protrude the laterally-projecting cutting-tools accordingly for extending their cutting work outside the width 70 of the casing, and the ascending portions of the chains on reaching the lower extremities of the flaring sections of the guide-grooves in their path enter them and are converged into the straight sections of the grooves to 75 enable the chains to enter the corresponding sides of and pass through the casing without obstruction. The cutting-disk 6 takes up the space between the cutting planes of the chains, due to their lateral spreading toward 80 their lower portions. When the depth of the hole being excavated increases to the extent to which the primary length of the chains need reach or may be fed, each chain is separated and another bar, like the bar 10, is introduced and fastened between the two bars 10 and 8, and more links are added accordingly to the chains, which are again fastened to render the chains endless about the upper and lower sprocket-wheels. This manner of 85 lengthening the cutting apparatus may be repeated as often as required to enable it to excavate a hole to any desired depth, and, as required, new sections of casing, like the section 20, but preferably of equal length on all 90 sides, may be added one upon the other to case the hole substantially throughout its depth.

As will be understood, the material which is loosened by the cutting operation in forming the excavation is scooped and elevated out of it by the buckets 19.

To withdraw the cutting apparatus from the excavation, the chains should be severed and attached at their ends to and wound upon 105 take-up drums or the like to lift out the cutting apparatus, and the inserted bars and casing-sections may be removed in succession as they are raised out of the hole. Of course if the extent of work done is only 110 that performed without lengthening the cutting apparatus the latter may be withdrawn from the hole by turning the wheel 29 in the direction opposite that for feeding.

The precise construction shown and described of my improved machine, while the best now known to me, may be variously modified in matters of details by those skilled in the art without departure from my invention. Hence I do not limit my invention to 125 such particular details.

The terms "upper" and "lower" applied to the foregoing description and in the appended claims to designate the positions of the sprocket-wheels are merely relative and 130 will be understood to include other positions with relation to each other of the sprockets on the body of the machine and those at the operating parts of the chains.

What I claim as new, and desire to secure by Letters Patent, is—

1. In an excavating cutting-machine, the combination with a support, of upper sprocket-wheels and lower sprocket-wheels, endless cutting-chains each passing about a pair of said sprocket-wheels comprising an upper member and a lower member, a cutter-head rotatably supported between the lower sprocket-wheels and driving means for said sprocket-wheels and cutter-head, substantially as described.

2. In an excavating cutting-machine, the combination with a support, of upper sprocket-wheels and lower sprocket-wheels of greater diameter than said upper wheels, endless cutting-chains each passing about a pair of said sprocket-wheels comprising an upper member and a lower member, and driving means for the upper sprocket-wheels operating to rotate them in relatively contrary directions and cause the chains to travel accordingly, substantially as described.

3. In an excavating cutting-machine, the combination, with a support, of upper sprocket-wheels and lower sprocket-wheels of greater diameter than said upper wheels, endless cutting-chains each passing about a pair of said sprocket-wheels comprising an upper member and a lower member, a cutter-head supported between the lower sprocket-wheels to rotate with one of them, and driving means for the upper sprocket-wheels operating to rotate them in relatively contrary directions and cause the chains to travel accordingly, substantially as described.

4. In an excavating cutting-machine, the combination, with a support, of upper sprocket-wheels and lower sprocket-wheels of greater diameter than said upper wheels, endless cutting-chains each passing about a pair of said sprocket-wheels comprising an upper member and a lower member, said chains having, at intervals, cutting-teeth projecting laterally beyond their edges, a cutter-head rotatably supported between the lower sprocket-wheels, and driving means for the sprocket-wheels and cutter-head, substantially as described.

5. In an excavating cutting-machine, the combination with a support, of upper sprocket-wheels and lower sprocket-wheels of greater diameter than said upper wheels, endless cutting-chains each passing about a pair of said sprocket-wheels comprising an upper member and a lower member, guides for said chains diverging toward said lower sprocket-wheels, a cutter-head supported between the lower sprocket-wheels to rotate with one of them, and driving means for the upper sprocket-wheels operating to rotate them in relatively contrary directions and cause the chains to travel accordingly, substantially as described.

6. In an excavating cutting-machine, the combination with a support, of upper sprocket-

wheels and lower sprocket-wheels, endless cutting-chains each passing about a pair of said sprocket-wheels comprising an upper member and a lower member, said chains having, at intervals, cutting-teeth projecting laterally beyond their edges, a cutter-head rotatably supported between the lower sprocket-wheels, a casing surrounding said chains, guides for directing the chains in traveling through said casing, and driving means for the sprocket-wheels and cutter-head, substantially as described.

7. In an excavating cutting-machine, the combination with a support, of upper sprocket-wheels and lower sprocket-wheels of greater diameter than said upper wheels, endless cutting-chains each passing about a pair of said sprocket-wheels comprising an upper member and a lower member, said chains having, at intervals, cutting-teeth projecting laterally beyond their edges, a cutter-head supported between the lower sprocket-wheels to rotate with one of them, driving means for the upper sprocket-wheels operating to rotate them in relatively contrary directions and cause the chains to travel accordingly, a casing surrounding said chains, and guides diverging toward said lower sprocket-wheels for directing the chains in traveling through said casing, substantially as described.

8. In an excavating cutting-machine, the combination with a support, of a plurality of upper sprocket-wheels supported side by side thereon with their driving means, a plurality of lower sprocket-wheels, endless cutting-chains passing about said upper and lower sprocket-wheels and running in relatively contrary directions, tautening means for said chains and guides for the chains having straight parallel sections and lower diverging sections, substantially as described.

9. In an excavating cutting-machine, the combination with a support, of a plurality of upper sprocket-wheels supported side by side thereon with their driving means, a plurality of lower sprocket-wheels of greater diameter than said upper sprocket-wheels, endless cutting-chains passing about said upper and lower sprocket-wheels and running in relatively contrary directions, tautening means for said chains provided with chain-guiding grooves having straight parallel sections and lower diverging sections, and a casing about said chains, substantially as described.

10. In an excavating cutting-machine, the combination with a support, of a plurality of upper sprocket-wheels supported thereon with their driving means, a plurality of lower sprocket-wheels of greater diameter than said upper sprocket-wheels, endless cutting-chains passing about said upper and lower sprocket-wheels and running in relatively contrary directions, tautening means for said chains, provided with chain-guiding grooves having straight parallel sections and lower diverging sections, a cutting-head confined between said

lower sprocket-wheels to rotate with one of them, and a casing about said chains, substantially as described.

11. In an excavating cutting-machine, the combination with a standard, of a sleeve rotatably and vertically movable thereon, a bracket carried by said sleeve to move up and down with it on said standard, a plurality of upper sprocket-wheels journaled side by side on said bracket, a plurality of lower sprocket-wheels, a cutter-head supported between said lower sprocket-wheels to rotate with one of them, endless cutting-chains passing about said upper and lower sprocket-wheels, driving means on said sleeve and bracket operating to rotate said upper sprocket-wheels in relatively contrary directions to cause the chains to travel accordingly, and feed mechanism for lowering and raising said sleeve and bracket to move said chains relative to the work, substantially as described.

12. In an excavating cutting-machine, the combination with a standard, of a sleeve rotatably and vertically movable thereon, a bracket carried by said sleeve to move up and down with it on said standard, a plurality of upper sprocket-wheels journaled side by side on said bracket, a plurality of lower sprocket-wheels of greater diameter than said upper sprocket-wheels, endless cutting-chains passing about said upper and lower sprocket-wheels, driving means on said sleeve and bracket for actuating said upper sprocket-wheels to drive the chains in relatively contrary directions, tautening means for the chains, provided with chain-guiding grooves having straight parallel sections and lower diverging sections, a cutting-head confined between said lower sprocket-wheels to rotate with one of them, a casing about said chains, and feed mechanism for lowering said chains relative to the work, substantially as described.

13. In an excavating cutting-machine, the combination with a standard provided with a rack, of a sleeve rotatably and vertically movable thereon, a bracket carried by said sleeve to move up and down with it on said standard, a plurality of upper sprocket-wheels journaled side by side on said bracket, a plurality of lower sprocket-wheels of greater diameter than said upper sprocket-wheels, endless cutting-chains passing about said upper and lower sprocket-wheels, driving means on said sleeve and bracket for actuating said upper sprocket-wheels to drive the chains in relatively contrary directions, tautening means for the chains provided with chain-guiding grooves having straight parallel sections and lower diverging sections, a toothed cutting-disk confined between said lower sprocket-wheels to rotate with one of them, a casing about said chains, and a worm-gear feed mechanism on said bracket, carrying a pinion meshing with said rack and forming means for lowering and raising said sleeve

and bracket to move said chains relative to the work, substantially as described.

14. In an excavating cutting-machine, the combination with a standard, of a sleeve rotatably and vertically movable thereon, a bracket carried by said sleeve to move up and down with it on said standard and provided with a head containing curved slots, a plurality of upper sprocket-wheels journaled side by side on said bracket, a plurality of lower sprocket-wheels, endless cutting-chains passing about said upper and lower sprocket-wheels, upper and lower tautening-bars adjustably connected together and confined within said chains, and adapted to be adjustably fastened at the upper bar to said slotted head, chain-guiding grooves in said bars, a casing about said chains and bars, driving means on said sleeve and bracket for actuating said upper sprocket-wheels to drive the chains in relatively contrary directions, and feed mechanism for lowering and raising said sleeve and bracket to move said chains relative to the work, substantially as described.

15. In an excavating cutting-machine the combination with a standard, of a sleeve rotatably and vertically movable thereon, a bracket carried by said sleeve to move up and down with it on said standard, and provided with a head containing two sets of concentric curved slots, a plurality of upper sprocket-wheels journaled side by side on said bracket, a plurality of lower sprocket-wheels, endless cutting-chains passing about said upper and lower sprocket-wheels, upper and lower tautening-bars adjustably connected together and adapted to be adjustably bolted through the upper bar to said head in either set of said slots, chain-guiding grooves in said bars, a casing about said chains and bars, driving means on said sleeve and bracket for actuating said upper sprocket-wheels to drive the chains in relatively contrary directions and feed mechanism for lowering and raising said sleeve and bracket to move said chains relative to the work, substantially as described.

16. In an excavating cutting-machine, the combination with a standard, of a sleeve rotatably and vertically movable thereon and carrying the beveled gears u , v , a bracket mounted on said sleeve to move up and down with it and provided with a tubular bearing having journaled in it a hollow shaft k carrying on one end a sprocket-wheel m and on its other end a beveled gear l meshing with said gear v , a shaft n journaled in said hollow shaft and carrying at one end a sprocket-wheel p and at its other end a beveled gear o meshing with said gear u , lower sprocket-wheels 3, 4, endless cutting-chains passing about the upper and lower sprocket-wheels and running in relatively contrary directions, tautening means for said chains, and feed mechanism for lowering and raising said sleeve and bracket to move said chains relative to the work, substantially as described.

17. In an excavating cutting-machine, the combination with a standard, of a plurality of upper sprocket-wheels supported side by side thereon with their driving means, a plurality of lower sprocket-wheels, endless chains passing about said upper and lower sprocket-wheels and running in relatively contrary directions and each formed of a series of links provided with headed stems on their inner sides and carrying on their outer sides cutting-tools some of which project beyond the edges of the links, and tautening-bars for said chains, provided with grooves having straight parallel sections and lower diverging sections for receiving said stems and guiding the chains, substantially as described.

18. In an excavating cutting-machine, the combination with a standard, of a plurality

of upper sprocket-wheels supported side by side thereon with the driving means, a plurality of lower sprocket-wheels, endless chains passing about said upper and lower sprocket-wheels and running in relatively contrary directions and each formed of series of links provided with headed stems on their inner sides and carrying on their outer sides elevator-buckets and cutting-tools, some of which latter project beyond the edges of the links, and tautening-bars for said chains, provided with grooves having straight parallel sections and lower diverging sections for receiving said stems and guiding the chains, substantially as described.

TAYLOR E. DANIELS.
